US0D1007783S

(12) **United States Design Patent** (10) **Patent No.:** **US D1,007,783 S**
(45) **Date of Patent:** **** Dec. 12, 2023**

(54) **PET SCRATCH BOARD**

(71) Applicant: **SHANGHAI LANPIN HAIZHUO TECHNOLOGY CO., LTD.**, Shanghai (CN)

(72) Inventor: **Chuanpeng Ning**, Shanghai (CN)

(73) Assignee: **SHANGHAI LANPIN HAIZHUO TECHNOLOGY CO., LTD.**, Shanghai (CN)

(**) Term: **15 Years**

(21) Appl. No.: **29/890,190**

(22) Filed: **Apr. 20, 2023**

(51) LOC (14) Cl. **30-06**

(52) U.S. Cl.

USPC **D30/160**

(58) **Field of Classification Search**

USPC **D30/158; D32/17, 18, 21**

CPC **A01K 15/024**

See application file for complete search history.

Howard M. Cohn

(57) **CLAIM**

The ornamental design for a pet scratch board, as shown and described.

DESCRIPTION

FIG. 1 is a perspective view of a pet scratch board showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

FIG. 12 is an enlarged view of portion 12 shown in FIG. 3;

FIG. 13 is an enlarged view of portion 13 shown in FIG. 4;

FIG. 14 is an enlarged view of portion 14 shown in FIG. 5;

and,

FIG. 15 is an enlarged view of portion 15 shown in FIG. 7.

The dot-dash broken lines represent boundaries of the enlarged portions and form no part of the claimed design.

1 Claim, 15 Drawing Sheets
